(57) **CLAIM**

The ornamental design for an interchangeable self-locking spring loaded quick connect apparatus for cable, as shown and described.

DESCRIPTION

FIG. 1 is a front, top, right side perspective view of an interchangeable self-locking spring loaded quick connect apparatus for cable embodying our new design;

FIG. 2 is a rear, bottom, right side perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof, the bottom plan being a mirror image; and,

FIG. 8 is a top plan view thereof, shown in a different position. The broken lines shown represent unclaimed subject matter and form no part of the claimed design.
